AUTOMATIC BANK ALARM SWITCH

Grover C. Moutray, Colorado Springs, and Ralph
J. Pendergrast, Manitou Springs, Colo.

Application August 24, 1937, Serial No. 160,564

1 Claim. (Cl. 200—54)

Our invention relates to switch controlled alarms for bank vaults and the like and our object is to provide a switch of this class adapted to be operated by a swinging door. Other objects will appear as the description progresses.

This alarm switch is intended to be used and operated in association with the automatic day-light hold up protector invented by Grover C. Moutray, a joint inventor of this switch, and patented under Patent No. 1,773,351.

Figures 1, 2 and 3 represent front views of the switch without a cover plate; Fig. 4, a schematic drawing showing the switch in position on the door jamb of a bank vault and the electric circuit connected up with a control switch, a battery and a bell, the vault door being shut; and Fig. 5, a schematic drawing showing the vault door open and the circuit connected up with the control switch, battery and bell.

Although we show the preferred embodiment of our invention we do not thereby limit ourselves to the precise form shown but wish it understood that within the scope of what is hereinafter claimed, various changes in the precise details may be made without departing from the spirit of the invention.

Our device comprises a housing 1, an insulation block 3, a pair of oscillating arms 4—5, a main terminal 6, a pair of contact terminals 7—8, a pair of binding posts 9—10 and a spring controlled plunger.

The housing 1 is provided with holes 12 and is adapted to be secured to the door jamb 13 of the bank vault by screws or bolts 20 running through holes 12 into the jamb 13, as shown in Figs. 4 and 5.

The oscillating arms 4—5 are pivotally mounted in a metallic block 14 at 15—16 respectively. A spring 17 connects arms 4—5 and normally holds said arms in contact with terminals 7—8, respectively, as shown in Fig. 2. A wire 18 runs from terminal 7 to binding post 9 and a wire 19 runs from terminal 8 to binding post 10.

The plunger is provided with a head portion 22, a spring holding portion 24 and a depending lug 25 and is slidably mounted in the housing 1 so that normally the head portion 22 extends outside the housing and the lug 25 is positioned between the arms 4—5. A compression spring 26 is disposed about the spring holding portion 24 between the head portion and the guide lug 27 in which the portion 24 is slidably mounted.

The night circuit shown in Fig. 4 is connected up as follows: A wire 30 from main terminal 6 to a bell terminal 31 of the bell 32; a wire 34 from

a bell terminal 35 to the battery 36; a wire 37 from the battery 36 to a terminal 38 of the control switch 39; the switch arm 40 contacting the terminal 41; a wire 42 from terminal 41 to binding post 10, and wire 19 from binding post 10 to terminal 8.

The day circuit shown in Fig. 5 is connected up as follows: The wire 30 from main terminal 6 to terminal 31 of the bell 32; wire 34 from terminal 35 to the battery 36; wire 37 from the battery 36 to terminal 38 of the control switch 39; switch arm 40 to terminal 48 of the control switch; wire 43 from terminal 48 to binding post 9, and wire 18 from binding post 9 to terminal 7. It will be observed that the night and day circuits are the same up to the control switch 39.

A push piece 50 is mounted on the bank vault door 51 as shown in Figs. 4 and 5. The push piece is bolted to said door by bolts 52 and is positioned so as to strike the head portion 22 of the plunger 20 and force said plunger within the housing 1, when the door is moved shut.

The spring 26 normally holds the plunger in the position shown in Fig. 1, but when the vault door 51 is shut the plunger is in the position shown in Fig. 3. When the vault door is shut for the night, the switch arm 40 is swung to the position shown in Fig. 4 so as to contact terminal 41. This circuit is designated the night circuit. While the vault door is shut, the push piece 50 presses 30 against the head portion 22 of the plunger and causes the lug 25 to hold arm 5 out of contact with the terminal 8. If the door 51 is now opened, the pressure against the plunger will be released and the spring 26 will force the head portion 22 35 outside the housing and thereby move lug 25 away from the arm 5 and permit the spring 17 to pull arm 5 into contact with terminal 8, thereby closing the circuit and permitting the battery to ring the bell until the circuit is broken. If therefore, 40 a robber attempts to open the vault door, the alarm is automatically sounded. The alarm bell is placed outside the vault in any desired location either in the building or in another building as for example, police headquarters.

In the morning when the banker desires to open the vault without sounding the alarm, he moves the switch arm 40 out of contact with the terminals 41 and 48 so that the circuit will be incomplete even when the arms 4—5 contact terminals 7—8. After the vault door is opened, the banker moves the switch arm 40 into contact with terminal 48 and thereby forms the day circuit. If now the door is shut, the push piece 50 forces the plunger inward of the housing and 55

moves the lug 25 away from arm 4 permitting arm 4 to contact terminal 7 which completes the day circuit and sounds the alarm. If therefore, a bandit attempts to imprison the banker in the 5 vault, the alarm will be automatically sounded.

When the previously mentioned automatic day-light hold up protector is used in association with our switch and alarm, the said protector catches the vault door when the lug 25 is in the position 10 shown in Fig. 2, and since arms 4—5 in this position are in contact with terminals 7—8, respectively, the alarm sounds regardless of which circuit is in use at the time.

If the night circuit is in use, the banker may 15 sound an alarm by moving arm 49 of the control switch 39 from terminal 41 to terminal 48. If the day circuit is in use he may sound an alarm by moving arm 40 to contact terminal 41.

We contemplate using a pilot light in association with the control switch so that whenever 20 the arm 40 is out of contact with both terminals

41—48, the pilot light is on. This will test the system as to hook up and also remind the banker the alarm system is not connected up.

Having thus described our invention, what we desire to secure by Letters Patent is:

In a bank alarm switch, the combination of a vertically disposed housing; an insulation block disposed in the lower portion of said housing; a metallic block mounted on the lower portion of said insulation block; a pair of oscillating 10 arms pivotally connected to said metallic block and extending upward; a spring connecting said arms; a pair of contact terminals spaced from each other and mounted in the upper portion of said insulation block between said arms; a 15 plunger slidably mounted in the upper portion of said housing and provided with a depending lug disposed between said arms; and a wire running from each contact terminal.

GROVER C. MOUTRAY.

RALPH J. PENDERGRAST.
